United States Patent Office

Des. 209,003
Patented Oct. 24, 1967

209,003

CANDLESTICK

Wallace W. Ward, Chatham, N.J., assignor to Diecasters
Inc., Closter, N.J., a corporation of New Jersey

Filed Apr. 5, 1967, Ser. No. 6,539

Term of patent 14 years

(Cl. D48—2)

FIG. 1 is a top plan view of the candlestick showing my new design;

FIG. 2 is a side elevational view thereof.

The bottom is plain.

I claim:

The ornamental design for a candlestick, as shown and described.
